UNITED STATES PATENT OFFICE.

LEWIS E. WATERMAN, OF MOLINE, ILLINOIS.

CORN-PLANTER.

SPECIFICATION forming part of Letters Patent No. 336,772, dated February 23, 1886.

Application filed October 28, 1884. Serial No. 146,697. (No model.)

To all whom it may concern:

Be it known that I, LEWIS E. WATERMAN, of Moline, in the county of Rock Island and State of Illinois, have invented certain new and useful Improvements in Corn-Planters; and I do hereby declare the following to be a full, clear, and exact description of the invention, such as will enable others skilled in the art to which it appertains to make and use the same.

My invention relates to an improvement in corn-planters, and particularly to that class of planters in which the droppers and drills are located on a swinging bar attached to the front end of a truck, the latter being adapted to support the driver, and the wheels of the truck to serve as coverers.

The object of my invention is to provide an improved system of levers for regulating the depth of cut of the drills; a further object being to provide an improved construction of the drills and truck-spindles, whereby the drills and covering-wheels may be laterally adjusted; a further object being to provide a sliding bottom plate and blanks, whereby the seed-plate may be slid or swung out of position and a blank substituted therefor; a further object being to provide improved mechanism for operating the seed-plate and dropper-gate or lower valve, whereby the plate is positively rotated and locked against displacement and the dropper-gate or lower valve caused to act independently of the seed-plate; a further object being to provide mechanism whereby the dropper may be operated either by a check-fork or by the truck-wheel or by the driver.

With these ends in view my invention consists in certain features of construction and combinations of parts, as will be hereinafter described, and pointed out in the claims.

In the accompanying drawings, Figure 1 is a view of the planter in perspective, taken from the rear, one of the truck-wheels being removed. Fig. 2 is a vertical longitudinal section through the center, showing the drills and boxes in an elevated position. Fig. 3 is the same, showing the drills and boxes in a depressed position. Fig. 4 is a view of one of the droppers in vertical section. Fig. 5 is a rear view of the same. Fig. 6 is a top plan view of the rotating seed-plate and operating mechanism connected therewith. Fig. 7 is a detached view

of the double pawl for operating the seed-plate. Fig. 8 is a detached view of the adjustable rest. Fig. 9 is a detached view of the gravity-latch for holding the seed-plate in position, and Fig. 10 is a detached view of the adjustable axle-spindle. Figs. 11 to 18, inclusive, represent modifications.

A A represent the truck-wheels having broad rims or faces, and mounted on laterally-adjustable spindles *a*, secured to the axle B. The spindles *a* are provided on their inner ends with castings *a'*, which are clearly represented in Fig. 10, and which curve downwardly from the spindles, and then extend horizontally in the form of elongated rectangular-shaped boxes having their upper portions cut away except at their inner ends, in which boxes the ends of the axle B are adapted to fit and slide. The lower faces of the castings *a'* are provided with elongated closed slots *a''*, and a series of depressions, *a''*, forming bolt-head rests. Bolts *b*, passing upwardly through the slots *a''*, axle B, and side rails, C, are provided with nuts *b'* on their upper ends, which, being turned on, draw the bolt-heads into their rests and secure the spindles and side rails securely to the axles. By loosening the nuts and driving the bolts downwardly until their heads are out of the rests *a''*, the castings *a'* may be moved laterally on the axles the required distance and the bolts drawn home again without removing a bolt and in a very short space of time.

The ready and simple adjustment of the spindles above described becomes a matter of very great importance in a planter, as will more plainly appear hereinafter when the lateral adjustment of the drills is explained. The side rails, C, are secured to the axle B by the bolts *b*, as described, and are connected at their rear ends by a cross-bar, *c*. A cross-bar or sill, D, is hinged to the forward ends of the rails C, and has a dropper and drill secured to it near each end outside of the rails C. The hounds *d* are also secured on the bar D between the rails C, the rear ends of the hounds coming together or nearly together at a point a short distance forward of the axle B. The forward ends of the hounds are connected by a cross-bar, *d'*. The tongue E is hinged at its rear end to the bar D, and is secured against lateral motion on the cross-bar *d'*, as follows: The bar

d' is recessed transversely at *d*² to receive the back of a wedge, *d*³. The face of the wedge receives the lower face of the tongue, the edges of the wedge *d*³ being provided with upwardly-extending lips *d*⁴, which engage the sides of the tongue. The wedge is further provided with a vertical elongated slot, *d*⁵, centrally located, through which a draw-bolt, *d*⁶, passes, said bolt passing also through the tongue and cross-bar *d*⁷, and locks the tongue snugly to the wedge and cross-bar. By adjusting the wedge *d*³ forward and backward the tongue is vertically adjusted to suit the heights of different teams. The drills or runners *F* are curved, as shown, the upper ends being secured to the bar *d*⁷ and their heels to the lower ends of the standards *G*, which standards also serve as dropping-throats. The upper ends of the dropping throats or standards *G* are secured to the under side of the bar *D*, and as the bar *D* or truck is rocked or tilted on its hinges the heels of the drills are elevated or depressed and caused to cut a shallower or a deeper furrow. The means for tilting this bar *D* and thereby regulating the depth of furrow form an important part of my invention, and consist of the following devices; A curved standard, *H*, is rigidly secured at its lower end to the axle *B* at or near the center thereof, and is provided at its upper end with a driver's seat, *h*. The standard *H* is further provided with a slot, *h*¹, just above the axle *B*, in which a lever, *h*², is pivoted, its short end extending forwardly. A lever, *h*³, is pivoted to a toothed sector, *h*⁴, rigidly secured between the rear ends of the hounds *d*. The lever *h*³ has its short arm extending rearwardly. The short arm of *h*³ is preferably bifurcated, and the short arm of *h*² is pivotally secured to *h*³ between the branches of its bifurcated end. The long arm of lever *h*³ terminates in a handle, *h*⁵, and the same lever is also provided with a foot-rest, *h*⁶, located just below the handle for applying foot-power to the lever. A pawl, *h*⁷, is pivoted to the lever *h*³ in position to engage the toothed portion of the section *h*⁴, and extends rearwardly past the lever *h*² to admit of being operated by the foot of the driver. It (the pawl) is also connected with a hand-lever, *h*⁸, by a link or rod, *h*⁹, by which construction the hand as it grasps the handle of the lever will lift the pawl out of engagement with the teeth of the sector. Suppose the levers to occupy the position represented in Fig. 2. The drills being elevated and locked in their elevated position by the pawl *h*⁷ in contact with the sector, the drills may be depressed in either of the following ways: The driver may reach forward and grasp the handle *h*⁵, thereby releasing the pawl *h*⁷ of lever *h*³, and draw the handle rearwardly; or, he may press the short arm of either lever with one foot and release the pawl *h*⁷ with the other. In either case the levers and drills will be thrown into the depressed position shown in Fig. 3; and locked in that position by the pawl *h*⁷. If it be desirable to make the drills

cut deeper than when in the normal depressed position shown in Fig. 3, the pressure of the foot on the rest *h*⁶, or the forward pressure on the handle *h*⁵, will force the heels of the drills downwardly. The drills are also automatically forced into the ground by the draft of the team, in the following manner: On the tongue is placed a sliding or swinging block, *i*, to which the double-trees are attached. A draw-rod, *I*, connects the sliding block *i*, or double-trees attached thereto, to a lever, *h*³, for example, at a point above the pivotal point of the lever, and thereby allows the draft of the team to operate the lever *h*³ in the direction to force the runners into the ground with a yielding force, which is automatic, in hard or soft ground. An adjustable stop, *i*', secured on the tongue, determines the forward motion of the block *i*. Thus, suppose the runners to be forced out of the ground, the double-trees and sliding block are drawn back from the stop, which action is against the draft, but the draft in turn slides the block forwardly and forces them down again. The draft will be found sufficient to force the runners down without the aid of either foot or hand lever, and I do not, therefore, wish to confine myself to using the several means indicated above in combination. This matter of causing the drills to cut deeper or shallower at pleasure is a matter of considerable importance where the ground is uneven, for the purpose of planting the seed at a uniform depth. The levers are thrown from the position shown in Fig. 3, where the drills are depressed, back to the position shown in Fig. 2, where the drills are elevated, by the pressure of the foot on the rear end of the lever *h*³.

From the above construction it will be observed that the driver can depress, elevate, and regulate the depth of cut of the drills by either his foot or hand, or by means of the draft of the team. When the latter is used, the pawl *h*⁷ is only useful in holding the drills in an elevated adjustment.

K represents one of the seed-boxes. Its bottom *k* is provided with a circular opening, *k*¹, beneath which the seed-plate *k*² is located in close contact with the bottom. The bottom *k* is provided with laterally-extending projections *k*³, which rest on the upper side of the bar or sill *D* and lap over on its sides. Bolts *k*⁴ pass through *D* and *k*³, and secure the box *K* rigidly to the bar *D*. The seed-plate *k*² is pivotally mounted at its center on a movable floor-plate, *L*, and provided with a circular row of boxes, *l*, each adapted to hold the desired number of kernels to plant a hill, and with a set of teeth, *l*', on its periphery, by means of which it is rotated. The floor-plate *L* is pivoted at one end between the projection *k*³ and the bar *D*. A blank, *l*', is secured to the plate *L* by means of a curved arm, *l*², which extends from near the pivotal point of *L* around about one-third of the periphery of *k*², just above the teeth *l*'. The upper surface of the blank *l*' is in a plane with the upper

surface of the plate k^2 , and the end of the blank toward k^2 is made concave to conform to the periphery thereof. The blank is sufficiently large to cover the circular opening k' in the bottom of the seed-box. By this construction the seed-plate may be swung from the box, and the blank l' follows its motion and takes its place beneath the box when it is removed. Thus a change of the seed-plates may be accomplished in a moment of time, and the plate returned to its position beneath the box K without scattering or disturbing the seed therein. The swinging floor-plate L is locked in its position beneath the seed-box by a gravity-latch, M , or its equivalent. The projections k^2 are provided with rearwardly extending arms or lugs m , provided with suitable bearings, in which a rock-shaft N , is journaled. The shaft N is provided with clutches n loosely mounted thereon, which take against a shoulder, n' , on a rigid collar or enlarged portion of the shaft when drawn over toward the front; but either clutch will admit of the shaft completing a half-revolution over toward the front without disturbing the other clutch. Each clutch is provided with an operating-arm, n^2 . The clutch on the end of the shaft N has its arm n^2 connected with the short arm of the fork-lever, O , which is adapted to be operated by a check-rower wire in the ordinary manner. The clutch n , located on the shaft N , inside of the box K , is connected with the end of an operating-lever, P , pivotally secured to the side rail near the axle B , the upper end of the lever P being adapted to receive the foot of the driver by which the rock-shaft N may be operated. The lever P may also be operated by a cam-toothed wheel, p , revolving with the truck-wheel and engaging a projection, p' , on the lever P . The rock-shaft N receives its forward motion only by the means above described. It is returned by the tension of a spring, p^2 , attached to it and the rear ends of the bounds or other convenient point. An upwardly extending arm, Q , is formed integral with or secured to the shaft N at a point directly in the rear of the outside teeth on the seed-plate. The arm Q is provided with an oblong vertical slot, q , having an upper portion, in which a push-pawl, R , is pivoted, and a lower portion in which a rebounding stop, r , is pivoted, so that the stop r travels slower than the push-pawl R for the purpose of diminishing the space between their working-faces. Thus by having r and R pivoted on a long and short arm, respectively, the stop-pawl r will remain in front of a tooth until the push-pawl has receded to a position behind the next preceding tooth, thus preventing more than one tooth to pass at a time. R and r are arranged to operate in conjunction with one another, as follows: As the shaft N is rocked forwardly, the push-pawl R , having a shoulder, r' , on its under face, takes against a tooth, l' , on the seed-plate and rotates the seed-plate the distance between the corresponding faces of two consecutive teeth. As the shaft N is returned by the action of the spring p^2 , the pawl R rises by means of an incline, r^2 , in the rear of the shoulder r' , over the tooth l' 70 next preceding the one just engaged, and falls in position to engage this tooth l' when the shaft N is rocked forwardly again. The return of the shaft N has also brought the shouldered end r^3 of the stop r rearwardly in 75 close proximity to the tooth l' first engaged by the pawl thereby, preventing the seed-plate from rotating forwardly until pushed by the pawl R , or, if the stroke is not complete, the end r^3 will engage the next succeeding tooth and return the plate to its original position. The stop r serves the further purpose of lifting the pawl R out of contact with the teeth on the seed-plate. For this purpose the forward end of r is beveled, as shown in Fig. 85 4, and an adjustable rest, S , is arranged to slide rearwardly to a point where the beveled end r^4 of the stop r will slide up on it as R and r are forced forwardly, and thereby lift itself and the pawl R , the forward end of 90 which rests on r , out of contact with the teeth. When so lifted, the seed-plate remains stationary and allows only one side of planter to operate, which is found convenient in planting point-rows or for leaving out a row. Again, 95 an outwardly-extending shoulder, r^5 , on the end of r engages the front edge of the projection k^3 , and limits the length of the return stroke of the shaft N . A stop or draw pawl, s , pivoted to a lug, s' , on the shaft N , is adapted 100 to engage a tooth on the inside edge of the seed-plate, and serves to hold the plate against a retrograde displacement and also to complete a forward stroke of the seed-plate when it fails from any cause to advance the full distance of two successive teeth by the action of the push-pawl R . It accomplishes this as follows: The hook s^2 on or near the end of the stop s falls over a tooth when the forward stroke of the shaft N is about two-thirds completed. 105 If, now, the stroke should fail at this point for any reason, the pawl R would not take on the next preceding tooth when returned, and the seed-plate would fail to deposit its load, but the hook s^2 as the shaft returns will draw 110 on the tooth it is in contact with and thereby rotate the plate sufficiently to complete the stroke.

It is evident that a stop to prevent the forward motion of the seed-plate might be attached at different points on the shaft from those shown, and accomplish, essentially, the same result. I do not wish, therefore, to confine myself strictly to the above-described form and arrangement of parts. A broad-mouthed 125 funnel, T , is secured in lateral adjustment to the rear of the bar D , beneath the opening in the floor-plate, for the passage of the seed. The lower end of T is over or slightly within the broad upper end of the dropping-throat t 130 in the standard G . The upper end of the standard G is provided with a horizontal plate or flange, t' , to which the standard G is firmly secured. The plate t' is provided with a series

of perforations, t^2 . Two bolts, t^3 , are set in the bar D with their threaded ends projecting below the bar. The standard G is secured to the under side of D, in different lateral adjustments, by passing two of the perforations t^2 over the ends of the bolts t^3 , and turning on the nuts t^4 . The breadth of the upper end of the throat will admit of a considerable lateral change in the standard G without carrying the lower end of the funnel T outside of it, while the funnel itself may be laterally adjusted by means of the draw-bolts t^5 passing through the oblong closed slots t^6 . The lateral adjustment of the drills with the dropping-throats located in their standards, requires a corresponding adjustment of the truck-wheels, which act as covering-wheels.

The simple adjustment of the truck-wheels has been explained. That, taken in connection with the means for adjusting the standards, forms a complete and quickly-executed adjustment for increasing or diminishing the space between the rows without changing the boxes.

The slide U, for discharging the seed at the heel of the drill, is operated by a gravity or spring dog u , pivotally secured to the upper end of its shank u' . The slide is held in position by a closed slot, u^2 , at the heel of the standard G, through which it passes, and by a two-arm guide, V, which partially embraces the shank u' . The guide V is secured to the back of the standard G in vertical adjustment, whereby the dog u is caused to release itself from the shaft N at an earlier or later part of the stroke. The shaft N is provided with a rearwardly-extending elongated flange or shelf, v , on the rear edge of which the dog u takes, in whatever lateral adjustment the standard may be secured. The dog u is constructed to release itself from the rock-shaft at or near the end of the first half-stroke, and the slide returns to its closed position regardless of the finish of the stroke, thus catching the seed which is being or about being discharged from the throat.

Fig. 11 represents the lever h^3 pivoted to a sector having slanting teeth, whereby the lever is allowed a free motion in one direction but locked against motion in the opposite direction.

In Fig. 12 the toothed sector and pawl are used with the foot-levers only, and the pawl will hold the drills elevated when the three pivotal points are on line.

In Fig. 13 the toothed sector is provided with a rearwardly-extending arm, x , which may be secured in different positions on the lever h^3 , and the sector thereby rendered adjustable.

In Fig. 14 an adjustable stop, x' , is secured to the edge of a smooth sector, against which the pawl rests when the drills are depressed. When the drills are elevated, the pawl will be thrown over the stop x' , as the lever h^3 completes its stroke, by means of the connecting-rod. The side rails, C, are hereshown as projecting over the hounds, and wedge-shaped

blocks x^3 are interposed between the hounds and rails and connected with the sliding block on the tongue by rods x^4 , whereby the drills are depressed when the draft is applied.

In Fig. 16 the draw-rod is connected to an arm, y , on the bar D'. In Fig. 17 the draw-rod is capable of vertical adjustment on the lever h^3 , and is attached at its forward end to a vibrating arm, y' , to which arm the double-tree is also attached; and in Fig. 18 the pivotal connection between the two levers is movable with respect to the levers, and a link, z , binds the short arms of the two levers together.

The modifications represent a few of the many ways in which the levers for elevating and depressing the drills may be constructed and operated without departing from the spirit and scope of my invention.

Having fully described my invention, what I claim as new, and desire to secure by Letters Patent, is—

1. The combination, with a truck and a drill-section hinged thereto, of two levers, one secured to the truck and the other to the drill-section, the short arms of said levers being adapted to act reciprocally upon each other to elevate or depress the drill section, substantially as set forth.

2. The combination, with a truck and a drill-supporting frame hinged thereto, of two levers having their short arms pivotally secured together, one of the levers being pivoted to the truck and the other to the drill-supporting frame, whereby the drills are elevated and depressed, substantially as set forth.

3. The combination, with a truck and a drill-section hinged thereto, of two levers adapted to elevate and depress the drill-section, and a pawl secured to one of the levers, and engaging a sector secured to the drill-section for locking the drill-section in different vertical adjustments, substantially as set forth.

4. The combination, with a drill-section hinged to the truck and provided with a toothed sector located at its rear end, of a lever pivoted to the toothed sector, a lever pivoted to the truck and to the first-named lever, and a pawl pivoted to the first-named lever for engaging the toothed sector, substantially as set forth.

5. The combination, with a truck, a drill-section hinged thereto, and a lever pivotally secured to the truck, of a combined hand and foot lever pivotally secured to the drill-section and to the first-named lever, whereby the drills may be elevated or depressed either by the hand or foot, substantially as set forth.

6. The combination, with a front or drill section of a planter and a combined foot and hand operating lever, of a combined foot and hand operated pawl pivoted to the lever and engaging a sector rigidly secured to one of said sections, substantially as set forth.

7. The combination, with a seed-box, of a sliding floor-plate having the seed-plate journaled thereon, substantially as set forth.

8. The combination, with a seed-box, of a

laterally-swinging floor-plate having the seed-plate journaled thereon, substantially as set forth.

9. The combination, with a seed-box, of a laterally-swinging floor-plate having the seed-plate journaled thereon, and a blank secured to the floor-plate in close proximity to the upper surface of the seed-plate, substantially as set forth.

10. The combination, with a rotary seed-plate constructed to slide from under the seed-box, of a gravity-latch adapted to lock the seed-plate in its working position, substantially as set forth.

11. The combination, with a rotary seed-plate, a rock-shaft, and a pawl operated by said rock-shaft, of a movable stop located alongside of the pawl and adapted to lock the seed-plate against displacement and return the plate to its original position when a partial stroke has been made, substantially as set forth.

12. The combination, with a rotary seed-plate operated by a pawl secured to a rock-shaft, of a stop adapted to lock the seed-plate against displacement, return it when a partial stroke has been made, throw the pawl out of contact with the plate, and limit the return-stroke of the rock-shaft, substantially as set forth.

13. The combination, with a dropping-throat, a rock-shaft, and a gate for opening and closing the dropping-throat, of a gravity-dog attached to the gate and adapted to automatically engage and disengage the rock-shaft during the first part of its forward stroke, thereby opening and closing the gate, substantially as set forth.

14. The combination, with a dropping-throat and a rock-shaft, of a gate for opening and closing the dropping-throat, said gate being operated by the rock-shaft, and adjusting devices connected with the gate, whereby the shaft is caused to close the gate at an earlier

or later part of the stroke, substantially as and for the purpose set forth.

15. The combination, with a seed-plate and a dropping-throat gate, of a spring-actuated rock-shaft adapted to operate the plate and gate, substantially as set forth.

50

16. The combination, with the rock-shaft, of two clutches loosely mounted thereon, one connected with a check-rower fork and the other with a foot-operated lever, constructed as described, so that one clutch automatically remains idle when the other is in use, substantially as set forth.

17. The combination, with a seed-box and a laterally-adjustable dropping-throat, of an adjustable broad-mouthed funnel for transferring the seed from the seed-plate to the throat, substantially as set forth.

18. The combination, with a seed box and plate, of a dropping-throat provided with a broad mouth, whereby it may be laterally adjusted while the seed-box remains stationary, substantially as set forth.

19. The combination, with a laterally-adjustable dropping-throat and a gate for opening and closing the lower end of the throat, of a rock-shaft provided with a longitudinal flange or shelf adapted to operate the gate in the different lateral adjustments of the throat, substantially as set forth.

20. The combination, with a tongue and tilting runners, of double-trees secured to the tongue in a reciprocating adjustment, and devices connecting the double-trees with the tilting runners, whereby the latter are forced into the ground with a yielding force, substantially as and for the purpose set forth.

In testimony whereof I have signed this specification in the presence of two subscribing witnesses.

LEWIS E. WATERMAN.
